DAVID REGINALD DAVIES, OF DIDSBURY, ENGLAND, ASSIGNOR TO WESTINGHOUSE ELECTRIC & MANUFACTURING COMPANY, A CORPORATION OF PENNSYLVANIA

SWITCH MECHANISM

Application filed May 19, 1927, Serial No. 192,574, and in Great Britain June 18, 1926.

My invention relates to switch mechanisms and particularly to switch mechanisms of the separable or draw-out type.

Switch mechanisms of the above specified type employ movable structures carrying circuit breakers, with or without other accessory devices, that are adapted to be separated from fixed structures in which are provided the terminals of bus bars and cables which are to be connected through the circuit breakers carried by the movable draw-out portions. In such switch mechanisms, the bus bar and cable terminals and those of the circuit breakers and accessory devices on the draw-out portion are frequently of the plug-and-socket type, but, in switch gear intended for heavy currents, the separable terminals or contact members are of the interleaved knife-blade type, and the surfaces are carefully finished to afford good electrical contact over a considerable area when the terminals are in engagement.

Notwithstanding the above precaution, difficulties sometimes arise through overheating at the separable contact terminals unless the surfaces are pressed together to such a degree as renders the draw-out operation difficult.

The foregoing difficulties at the contacts may be avoided by providing bolts or screws by which the plates constituting the terminals may be firmly clamped together or pressed into contact after engagement of the two sets of terminals.

It is an object of my invention to provide an improved clamping device for this purpose.

It is another object of my invention to provide a switch mechanism of this type having a clamping device adapted, when moved into an operative position, to cause the blades of a set of terminals to approach each other simultaneously and press firmly upon the interposed blades of the other set of terminals.

It is a further object of my invention to provide an interlocking device associated with the clamping device so that, when the latter is in its operative position, separation

of the two portions of the switch gear is positively prevented.

These and other objects that may be made apparent throughout the further description of my invention are attained by the apparatus hereinafter described and illustrated in the accompanying drawings, wherein

Figure 1 is a side elevational view, partly in section, showing my invention applied to switch mechanism for a three-phase system.

Figure 2 is a front elevational view, showing the upper part of the fixed portion of the switch mechanism, the movable portion being omitted, and

Figure 3 is a plan view, more or less diagrammatic, corresponding to the upper portion of Fig. 1.

My invention will be more readily understood by referring to the drawings.

Preferably, the device comprises a shaft rotatably mounted transversely of a row of the terminals and provided with levers, toggles or cams corresponding to each terminal of the said row. Usually, the terminals in such bus structures may conveniently be arranged in a plurality of rows and it will be evident that the invention disclosed herein enables them all to be acted upon simultaneously through the intermediary of one shaft so that the blades in each terminal are firmly pressed into contact with each other when the shaft is rotated into one position, the pressure being relieved by rotating the shaft into another position.

The fixed portion 1 of the switch mechanism is provided with bus bars 2 and cable connections 3 in the usual manner, and the movable portion 4 which carries a circuit breaker 5 is adapted to slide toward and away from the fixed portion 1.

As seen in Fig. 1, each of the bus-bar terminals comprises a plurality of knife-blade contacts 6 between which other knife-blade contacts 7 of the corresponding terminals carried by the movable portion 4 are adapted to be interposed. The cable terminals, which are arranged directly beneath the bus-bar terminals, similarly comprise knife blades 8 carried by the fixed portion 1, the movable portion 4 carrying corresponding knife blades 9.

An insulating block 10 is disposed between the bus bar and cable terminals, and other insulating blocks 11 and 12 are arranged below and above said terminals, the former bearing upon a fixed portion of the switch casing and the latter being adapted to receive the pressure of a clamping device 13 which is superposed thereabove.

As seen from Fig. 2, the set of terminals carried by the fixed portion of the switch mechanism comprises three bus-bar terminals 14 disposed horizontally in a row and three cable terminals 15 similarly in a row therebeneath, as is usual in three-phase switch mechanisms of this kind.

The clamping device 13 comprises a transverse shaft 16 rotatably mounted in bearings 17 carried by the casing 1, as shown in Figs. 2 and 3. The shaft 16 is disposed directly above the insulators 12 of the bus-bar terminals 14. Upon the shaft 16 are secured three similar cams 18 corresponding to the row of three terminals 14 therebeneath, and between the insulators 12 and the cams 18 is interposed a plate 19 which assists in distributing the pressure equally upon the terminals and strengthens the structure. At each end of the shaft 16 is secured an arm 21, said arms being connected, at their free ends, by a handle 22. The handle 22 and arms 21 constitute the operating member for the clamping shaft, and between the arms 21 is secured a cross-bar 23 adapted to engage bosses 24, on the casing of the movable portion 4 when the parts are in the position shown in the drawings as shown in Fig. 3.

It will be readily seen that, when the switch mechanism is closed and the arms 21 are lowered into the horizontal position, as shown, the cams 18 press downwardly upon the plate 19 so that the insulating blocks 10, 11 and 12 and the blades 6 and 8 of all the bus bars and the cable terminals are forced together and tightly clamp the interleaved blades 7 and 9 of the terminals of the movable portion 4, thereby affording an excellent contact between the several pairs of terminals and avoiding the danger of overheating.

Upon moving the arms 21 to their uppermost position by means of the handle 22, the pressure on the plate 19 and the insulating blocks 10, 11 and 12 is relieved, permitting the movable portion of the switch mechanism to be moved away from the fixed portion or towards it so as to disengage or reengage the knife-blade contacts, as the case may be. It will be noted that, when the cam operating lever is in its horizontal or operative position, the operating member embraces the casing of the movable portion 4 so that the movable portion of the switch mechanism is locked in the closed position, that is to say, with the terminals in engagement, the structures can not be separated from their closed position so

long as pressure is applied, by the clamping device 13, to the interleaved contact.

It is apparent from the foregoing, that the cam shaft with its associated cams may be located below the cable terminals or, with suitable modifications in the shape of the cams, may be located between the two rows of terminals, if desired. It will further be apparent that additional shafts with suitable cams may be provided to co-operate with the shaft above described, and that the latter shafts may be mechanically connected with the former. In some cases, the shaft or shafts with associated cams may be disposed on the movable portion of the switch mechanism and be arranged to bear on the terminals thereof in place of on the terminals of the fixed portion.

While I have illustrated and described but one embodiment of my invention, it will be apparent to those skilled in the art that other forms of levers may be employed for this purpose. The shaft 16, for example, may be readily adapted to operate toggles instead of cams to apply pressure to the terminals as above described. Many other changes, modifications, substitutions, additions and omissions may be made without departing from the spirit and scope of the appended claims.

I claim as my invention:

1. A switch mechanism comprising a stationary structure having a bus bar disposed therein, aligned sets of terminal members for the bus bar, a movable structure having disposed thereon a circuit breaker, terminal members for engaging and co-operating with the terminal members in the stationary structure, and positive clamp means for maintaining the contact members carried by the movable structure in firm contact relation with the contact member disposed in the stationary structure when the structures are in operative position, said clamp means including a cam and insulating spacers between the terminals of a set and between the cam and a terminal.

2. A switch mechanism comprising a stationary structure having bus bars, terminal members for the bus bars in superimposed relation and arranged in rows, a movable structure having disposed thereon a circuit breaker and contact members for engaging and co-operating with the contact members in the fixed structure, and means including a shaft rotatably mounted transversely of the rows of the terminal members and provided with cams, one only for each of said rows for applying pressure to the contact members when the structures are in operative position.

3. A switch mechanism comprising a stationary structure having fixed terminals of the interleaved knife-blade type, a movable structure having disposed thereon a circuit breaker and contact members of the inter-

- leave knife-blade type for engaging and co-operating with the fixed terminals and means for firmly clamping together the blades of the terminals and the corresponding contact members when they are in engagement and
- 5 an interlocking device associated with the said means so that when the latter is in its operative position the structures are positively prevented from being separated.
4. A switch mechanism comprising a stationary structure having bus bars disposed therein, contact members for the bus bars, a movable structure having disposed thereon a circuit breaker and contact members for engaging and co-operating with the contact members in the stationary structure and means for firmly clamping together corresponding contact members of both structures when they are in their operative position, the said means having an interlock associated therewith for positively preventing the separation of the structures so long as the clamping means is in its operative position.
5. A switch mechanism comprising two relatively movable structures, each structure having contact members disposed therein and adapted to engage and co-operate with the corresponding contact members of the other structure, a clamping device for the contact members having a mechanical connection for positively preventing the separation of the structure so long as the clamping device is in its operative position.
6. An electrical device having a plurality of horizontal rows of interleaved disconnect-contact members, the said contact members of different rows being disposed in aligned vertical relation, vertically aligned insulation blocks disposed between the contact members of separate rows and a single cam for simultaneously applying pressure to the aligned insulating blocks for positively clamping the contact members in closed relation and means for preventing the release of the respective disconnect-contact members when in one position and permitting the release of the disconnect-contact members when in another position.
7. The combination with a plurality of sets of interleaved cooperating separable contact members, of compression members between the sets and forming a stack of alternately disposed contact members and compression members and means for pressing the leaves and compression members together by applying pressure at the end of the stack to prevent separation of the contact members and to obtain good conductive contact between the cooperating members of each set.
8. The combination with a plurality of sets of cooperating overlapping separable contact members of compression members between the sets and forming a stack of alternately disposed contact members and compression members and means for pressing the contact
- members and compression members together by applying pressure at the end of the stack to prevent separation of the contact members and to obtain good conductive contact between the cooperating members of each set. 70
9. A switch mechanism comprising a stationary structure having bus bars disposed therein, terminal contact jaws for the bus bars, a movable structure having disposed thereon a circuit breaker and contact members for engaging the terminal jaws in the stationary structure and means preventing accidental withdrawal of the movable circuit breaker structure from the stationary bus structure comprising a device cooperating 80 with the jaws for locking the contact members against separation from the jaws.
- In testimony whereof, I have hereunto subscribed my name this twenty-eighth day of April, 1927.
